UNITED STATES PATENT OFFICE.

GEORGE JACOBS, OF ALLIANCE, OHIO, ASSIGNOR TO HARRY FREASE, TRUSTEE, OF CANTON, OHIO.

FILING-CABINET.

No. 922,589.

Specification of Letters Patent.

Patented May 25, 1909.

Application filed November 18, 1907. Serial No. 402,585.

To all whom it may concern:

Be it known that I, GEORGE JACOBS, a subject of the Emperor of Germany, residing at Alliance, in the county of Stark and State of 5 Ohio, have invented a new and useful Filing-Cabinet, of which the following is a specification.

The invention relates to a filing cabinet for bills of sales or accounts, as of a retail 10 merchant, and more particularly to that class of cabinets containing a series of leaves located face to face in upright echelon so that the upper edge of each leaf is exposed above the edge of the leaf in front of it, the leaves 15 being hinged or pivoted and adapted to be folded forward for the purpose of exposing and giving access to the sides of the several leaves.

A primary object of the improvement is to 20 provide means for individually and collectively connecting the leaves by gearings so that when folded forward they are neatly nested or collocated in a prone position within a space substantially equal to the area of 25 one leaf and the combined depth of all the leaves, and in this relation can be readily removed from the ordinary case and inserted in a safe or vault for security without consuming undue space therein.

30 A further object of the improvement is to provide means for automatically moving the uprightly disposed leaves forward and backward at the same time the leaves in front of them are lowered and raised, so that the forward one of the uprightly disposed leaves always occupies substantially the same vertical 35 plane and is therefore conveniently accessible for inserting and removing bills at the same distance from the forward side of the 40 cabinet.

Another object of the improvement is to provide means for counter-balancing the leaves individually so that when one or more leaves are started upward from the prone 45 position they are automatically thrown to and then remain in the upright position.

A further feature of the invention relates to the construction of the respective leaves whereby they are substantially made of a 50 piece of sheet metal placed between suitable frames on each side, which frames serve to properly stiffen the leaf and to divide it into a series of recessed compartments.

These objects and other minor ones are

attained by the construction, mechanism and arrangement illustrated in the accompanying drawings in which:

Figure 1 is a perspective view of the file cabinet containing a small number of leaves with one side of the case removed and having one leaf folded down and also partly broken away to expose a portion of the index; Fig. 2, a vertical section showing the arrangement of the leaves and some details of the bearing blocks; Fig. 3, an inner-side elevation of the series of bearing blocks as arranged obliquely for the normal upright position of the leaves, with some parts in section to show interior details; Fig. 4, an inner-side elevation of the bearing blocks as assembled in a vertical tier for the folded down prone position of the leaves, with some parts in section to show interior details; Fig. 5, a section on line 5—5, Fig. 4; Fig. 6, a section on line 6—6, Fig. 5; Fig. 7, an inside-forward perspective view of the bottom, intermediate and the top bearing blocks separated from their normal assembled position; Fig. 8, an inside rearward perspective view of the same blocks similarly separated; Fig. 9, a longitudinal vertical section of one intermediate bearing block; Fig. 10, a fragmentary perspective view showing details of the leaf, sheet and frame in a detached relation; Fig. 11, a vertical section of one leaf; Fig. 12, a perspective view of the leaves and bearing blocks removed from the case and showing the leaves folded down in a prone position for storing in a safe; Fig. 13, a side elevation of a cabinet containing a larger number of leaves, all in normal upright position, and having the near side of the case and the adjacent bearing blocks removed; and Fig. 14, a similar view showing the greater number of the leaves folded downward to expose one of the rearward leaves.

Similar characters refer to similar parts throughout the drawings.

The cabinet comprises the case 1, the bearing blocks 2, 2^a and 2^b, and the leaves 3. The case may be of any suitable form and construction and as shown is composed merely of the bottom 4, the back 5 and the sides 6, leaving the front and top open to afford a ready access to and operation of the leaves.

One set of bearing blocks is located parallel with and opposite to the other on each

inner end corner of the leaves, and the bottom blocks 2 are securely fastened as by means of rivets 7 to the base plate 8, on which is preferably provided the index 9. 5 The base plate and the bearing blocks thereon constitute a frame in which the leaves are mounted; and this frame is adapted to be detachably secured in the case by seating the base plate on the bottom 10 of the case with the pins or posts 10 therein protruded through the apertures 11 in the base plate.

Each bottom block 2 and intermediate block 2^a is provided with the upward-inward L flange 12, and each intermediate block 2^a and each top block 2^b is provided with the downward-outward L flange 13 which is adapted to interengage with the corresponding flange 12 of the 20 block immediately below, so that all the blocks while being securely held together are adapted to slide endwise one upon the other. The journal bearings 14 are provided on the inner sides of the blocks, in 25 which bearings the pivot pins 15 located on the inner-end corners of the leaves are adapted to be inserted and to operate; and the short rack-sections 16 are also provided on the inner sides of each intermediate and 30 top block, in which racks the pinion-wheel sections 17, located on the sides of the leaves concentric with the pivot pin, are adapted to mesh and to operate. By means of this mechanism it is evident that when 35 one leaf is rotated upward on its pivots, the bearing block next above with all the superimposed blocks will be moved backward at the same time, and the gearing is so proportioned that the longitudinal movement of each block caused by the rotation 40 of its actuating leaf from its prone to its upright position, is approximately equal to the interval occupied by one leaf which is preferably the same as the projection of 45 one upright leaf above another. The parts are so proportioned and arranged that when the leaves are all folded downward in a 50 rectangular pack and in close contact with each other and the bearing blocks will all be arranged in a vertical tier, as shown in Fig. 12; and it is evident that when the leaves are raised to their upright position the blocks will slide one upon another so 55 that the plane of the pivots of the respective leaves will incline upward and backward at an angle of approximately forty-five degrees, and that the leaves will be compactively collocated in an upright echelon, 60 as shown in Fig. 1.

The spiral springs 18 are located in the longitudinal bores 19 formed in the interengaging flanges of the respective blocks, and these springs are at all times held in 65 compression between the plates 20 fastened

on the forward end of each respective block, and the shoulder 21 formed in the flange of each respective upper block, and by extending the bore in the corresponding flange of the lower block beyond the shoulder 21 in 70 the flange of the upper block, it is evident that the energy of the spring is exerted to force the upper block backward. The strength of the spring is so proportioned that when the actuating leaf of each block 75 is folded forward and downward to its prone position, the increased leverage caused by the weight of the free end of the leaf will slightly more than counter-balance the energy of the spring; but that when the leaf has been started upward and backward from its prone position, the gradually lessened leverage caused by the approach of the free end of the leaf toward its upright position will soon permit the energy of the 80 spring to first counter-balance and then to overbalance the relatively lessened weight of the leaf, with the effect that the spring will then throw the leaf to its upright position and hold it there until it is forcefully 85 folded forward.

It is evident that two or more leaves can be rotated downward and upward in the same manner as described for a single leaf and, although acting in unison, each leaf will independently operate the bearing blocks of the upper leaves in the manner described for a single leaf, and that by reason of each leaf being individually counter-balanced, the friction between the leaves in such joint 90 movement will be eliminated, or reduced to a minimum. Referring to Figs. 13 and 14, it is furthermore evident that the upright leaf which is exposed will always stand in the same vertical plane with respect to the case, 95 irrespective of the number of leaves used, for the reason that the rotation of each leaf from its upright to its prone position automatically moves each superimposed bearing block forward a distance equal to the interval of 100 one upright leaf. For the purpose of sustaining the bearing blocks and of preventing any binding in the sliding of one block on another, the rollers 22 are preferably mounted on the rear part of the top blocks, which 105 rollers are adapted to travel on the horizontal ways 23 formed or attached on the inner walls of the sides of the case, but these rollers are not essential when a comparatively small 110 number of leaves are used. The top bearing blocks 2^b are provided with the stop-pins 24 against which the uppermost leaf is adapted 115 to rest when in its upright position.

Each leaf 3 is preferably made of the sheet-metal body 25 fastened between the preferably one-piece metallic frames on each side, 120 which frames are composed of the main or axial bars 26 and 26^a located along the inner edges of the leaves, and the ribs 27 which 125 extend laterally from the axial bars outward 130

on each face of the sheet-body, thus forming the leaf with a series of recessed compartments in each face. The sheet and the frames of each leaf are rigidly clamped and secured together as by means of the rivets 28 and when so clamped together constitute a substantial and comparatively inflexible leaf which is not liable to bend or twist in use. The pivot pins 15 and the cog wheel sections 17 are preferably formed on the end of the axial bar 26, which for that purpose is provided with the lugs 29 adapted to fit into the recesses 30 and 31 in the corners of the sheet-body and of the opposing frame. The spring clips 32 are provided in the recessed compartments, behind which clips the bills which are to be filed are adapted to be received and retained, and it is desirable to fasten plates as 33, on the free edges of the leaves which plates carry the numbers referred to in the index covering the series of bills which are filed in the particular leaves.

It will be understood that the scope of the invention is not limited to the use of the leaves for the purpose of filing bills as herein described, and also that while the use of the counterbalancing springs is desirable for the purposes set forth they are not essential for the proper operation of the other features of the invention.

The improvements in filing cabinets which are illustrated and described but not broadly claimed herein, are made the subject-matter of generic claims in a prior application for Letters Patent, filed August 17, 1907, Serial No. 388,966.

What I claim as my invention, and desire to secure by Letters Patent, is—

1. A case having track-ways on its sides, a detachable frame in the case including oppositely-located spring-controlled parallel tiers of endwise-slidable blocks having journal-bearings and rack-sections on their inner sides, and rollers on the top blocks adapted to travel on the track-ways; and a series of leaves having pivot-pins on the inner-end corners adapted to operate in respective block-bearings, and concentric pinion-wheel sections adapted to operate in the rack-sections of adjoining blocks.

2. A frame including oppositely-located spring-controlled parallel tiers of endwise-slidable blocks having journal-bearings and rack-sections on their inner sides, and a series of leaves having pivot-pins on the inner-end corners adapted to operate in respective block-bearings and concentric pinion-wheel sections adapted to operate in the rack-sections of adjoining blocks.

3. A frame including oppositely-located parallel tiers of endwise-slidable blocks having journal-bearings and rack-sections on their inner sides, and a series of leaves having pivot-pins on their inner-end corners adapted to operate in respective block-bearings and

concentric cog-pinion sections adapted to operate in the rack-sections of adjoining blocks.

4. A frame including a tier of endwise-slidable blocks having journal-bearings and rack-sections thereon, and a series of leaves having pivot-pins thereon adapted to operate in respective block-bearings, and concentric cog-pinion sections adapted to operate in the rack-sections of adjoining blocks. 70

5. A frame including oppositely-located parallel-tiers of endwise-slidable interengaging blocks, an intervening series of leaves respectively pivoted to the blocks and having gearing connections with adjoining blocks whereby the same are moved endwise when the leaves are rotated on their pivots, and controlling springs between the blocks. 80

6. A frame including oppositely-located parallel-tiers of endwise-slidable interengaging blocks, and an intervening series of leaves respectively pivoted to the blocks and having gearing connections with adjoining blocks whereby the same are moved endwise when the leaves are rotated on their pivots. 85

7. A frame including oppositely-located parallel-tiers of endwise-slidable blocks, an intervening series of leaves respectively pivoted to the blocks, and rack and pinion gearings connecting the leaves with adjoining blocks whereby the same are moved endwise when the leaves are rotated on their pivots. 95

8. A frame including a tier of endwise-slidable interengaging blocks, a series of leaves respectively pivoted to the blocks and having gearing connections with adjoining blocks whereby the same are moved endwise when the leaves are rotated on their pivots, and controlling springs between the blocks. 100

9. A frame including a tier of endwise-slidable interengaging blocks and a series of leaves respectively pivoted to the blocks and having gearing connections with adjoining blocks whereby the same are moved endwise when the leaves are rotated on their pivots. 105

10. A frame including a tier of endwise-slidable blocks, a series of leaves respectively pivoted to the blocks, and rack and pinion gearings connecting the leaves with adjoining blocks whereby the same are moved endwise when the leaves are rotated on their pivots. 110

11. A frame including oppositely-located parallel-tiers of endwise-slidable interengaging blocks, an intervening series of rotatable leaves respectively connected with the blocks, the leaves being normally located uprightly in echelon and when rotated to and from a prone position each leaf being adapted to move the superimposed blocks and leaves in the same direction the interval of one leaf, 115 and controlling springs between the blocks, and

12. A frame including oppositely-located parallel-tiers of endwise-slidable interengaging blocks and an intervening series of rotatable leaves respectively connected with the 120

blocks, the leaves being normally located uprightly in echelon and when rotated to and from a prone position each leaf being adapted to move the superimposed blocks and leaves in the same direction the interval of one leaf.

13. A frame including a tier of endwise-slidable interengaging blocks and a series of rotatable leaves respectively connected with the blocks, the leaves being normally located uprightly in echelon and when rotated to and from a prone position each leaf being adapted to move the superimposed blocks and leaves in the same direction the interval of one leaf, and controlling springs between the blocks.

14. A frame including a tier of endwise-slidable interengaging blocks and a series of rotatable leaves respectively connected with the blocks, the leaves being normally located uprightly in echelon and when rotated to and from a prone position each leaf being adapted to move the superimposed blocks and leaves in the same direction the interval of one leaf.

15. A series of leaves located face to face, 25 a tier of spring-controlled endwise-slidable interengaging blocks respectively pivoted to corresponding end corners of the leaves, and gearing connections between the leaves and adjoining blocks whereby the leaves are 30 adapted to be collocated either in echelon or in a rectangular pack.

16. A series of leaves located face to face, a tier of endwise-slidable interengaging blocks respectively pivoted to corresponding 35 end corners of the leaves, and gearing connections between the leaves and adjoining blocks whereby the leaves are adapted to be

collocated either in echelon or in a rectangular pack.

17. A series of leaves located face to face, 40 a tier of endwise-slidable interengaging blocks respectively pivoted to corresponding end corners of the leaves, and rack and pinion connections between the leaves and adjoining blocks whereby the leaves are adapted 45 to be collocated either in echelon or in a rectangular pack.

18. A cabinet including a series of rotatable leaves normally located uprightly in echelon with gearing connections whereby the 50 rotation of the leaves to a prone position collocates them in a rectangular pack and vice versa, and ways on which the top-leaf gearings are sustained.

19. A frame including oppositely-located 55 parallel tiers of endwise-slidable interengaging blocks, an intervening series of leaves respectively pivoted to the blocks and having gearing connections with adjoining blocks whereby the same are moved endwise when 60 the leaves are rotated on their pivots, and ways on which the top blocks are sustained.

20. A frame including a tier of endwise-slidable interengaging blocks and a series of leaves respectively pivoted to the blocks and 65 having gearing connections with adjoining blocks whereby the same are moved endwise when the leaves are rotated on their pivots, and a way on which the top block is sustained.

GEORGE JACOBS.
